(57) **CLAIM**

The ornamental design for a ceiling fan housing, as shown and described.

DESCRIPTION

FIG. 1 is a top perspective view of a ceiling fan housing showing our new design;

FIG. 2 is a bottom perspective view thereof;

FIG. 3 is a front elevational view thereof, the opposing rear elevational view being substantially the same thereof;

FIG. 4 is a left side elevational view thereof, the opposing right side elevational view being substantially the same thereof;

FIG. 5 is a top plan view thereof; and,

FIG. 6 is a bottom plan view therof.

The dashed lines in FIGS. 1 and 5 show environmental features, which are for illustrative purposes only and form no part of the claimed design.

The broken line showing of the opening where a support pole goes is included for the purpose of illustrating environmental structure and forms no part of the claimed design.
